LOCK

George H. Thacher, Melrose, Mass.

Application August 11, 1939, Serial No. 289,599

3 Claims. (Cl. 70—231)

The invention relates to an improvement in locks especially adapted for the locking of gas fixtures, although applicable, also, to many other connections where separate parts, or elements, are locked together, or the operation of a single part, or element, prevented.

The object of the invention is to provide a lock that will well serve the purpose for which it is designed, though of simple construction and relatively inexpensive; to provide, also, a lock that is self-locking when applied; one that gives no evidence to the uninitiated of the mode of its unlocking, and which can only be unlocked with a special and powerful tool.

15 The invention can best be seen and understood by reference to the drawings in which the lock is shown, together with various examples showing the mode of its application for the locking of gas fixtures.

20 Fig. 1 is a view showing the lock in perspective. Fig. 2 is a cross section on line 2—2 of Fig. 1. Fig. 3 is a view in perspective of the lock with tool applied for unlocking it.

25 Fig. 4 shows in perspective the application of the lock to one type of gas fixture.

Fig. 5 shows in perspective the application of the lock to another type of gas fixture.

30 Fig. 6 is a perspective of the locked fixture shown in Fig. 5 with the parts thereof disassociated.

Fig. 7 shows in perspective application of the lock to a still further type of gas fixture.

35 Fig. 8 is a perspective of the locked fixture shown in Fig. 7 with the parts thereof disassociated; and

40 Fig. 9 is a view partly in side elevation and partly in section of the lock and its unlocking tool, the unlocking tool being shown in cross section.

The lock comprises separate elements lockable together and of which 1 represents the keeper carrying element, for it is the element to which the bolt of the bolt carrying element 2, later to be referred to, is locked. The element 1 comprises a post, preferably made round. It has at its foot end a flange 3, or equivalent member such as one from which the post may extend, examples of which will later be referred to. On its side the post is provided with a slot 4 which forms a keeper for the bolt. This slot is preferably an annular slot extending circumferentially around the post.

45 The bolt carrying element 2 encircles the post to cover the slot 4 therein in the manner of a sleeve, with easy sliding fit on the post, and with

application from over the top end of the post. The element 2 is preferably made in the form of a cap, the element being provided with a bore 5 into which the post extends. The element 2 may be made rounding in form although preferably is made to simulate a nut. Though the element 2 extends well over the post for some distance above and below the slot 4 therein when the element 2 is in place, yet the length of the post is such that a space 6 will be left between the lower edge of the element 2 and the flange 3 on the post or equivalent member.

50 The element 2 is provided with a stepped opening within and through the side thereof for receiving a bolt assembly 8. This stepped opening includes a boltway 9 and a socket forming opening 10 in aligned extension of the boltway and with diameter larger than that of the boltway. Both the boltway and the opening 10 are preferably cylindrical in form. The boltway forms a slide-way for the bolt and opens at its inner end directly onto the slot 4 in the post when the elements 1 and 2 are combined. The socket forming opening 10 opens onto the exterior side of the element 2.

55 The bolt assembly 8 comprises a bolt comprising a shank 11 to the end of which is secured, preferably by riveting, a cap 12 the body 13 of which extends part way over the shank embracing it in the manner of a loose sleeve to leave an annular opening 14 between it and the shank, and the end of which provides a shoulder forming a stop 15. It is this enlarged portion of the bolt which slides within the boltway 9, providing a slideway therefor, and extends into the slot 4 in the post 1 when the bolt is in locking engagement with the post. At its outer end the bolt shank 11 is provided with a fixed head 16, the peripheral edge of which is stepped to provide an edge surface 17, and offset therefrom an edge surface 18 of slightly lesser diameter than that of the edge surface 17.

60 Located upon the shank of the bolt, but not fixed to it, is a washer 20. This washer is preferably cylindrical in form and is slightly larger diametrically than the head of the bolt. Arranged upon the shank 11 of the bolt and between the washer 20 and the end of the cap 12 is a coiled spring 21 which lies partially contained within the annular opening 14.

65 The whole assembly bears a determinate relationship to the stepped opening in the element 2 within which it is contained. When located therein the washer 20 and head 16 of the bolt assembly will lie contained within the socket forming opening 10. The washer 20 will lie at

the bottom of the opening with press fit against the circumferential side wall of the opening, thus becoming affixed to the element 2. The peripheral edge 17 of the head will clear the side wall of the opening but lie snugly thereto. The front face of the head will lie substantially flush with the face of the element 2, thus leaving a thin annular slit 22 around the peripheral edge 18 of the head and the adjacent wall of the opening within which it is contained. The head with the parts thus normally arranged will be drawn into contact with the washer 20 by the force of the spring 21 and the bolt will be held in a state of projection. Consequently if the element 2 be then combined with the post or element 1 the end of the bolt will then fit within the slot 4 of the post forming a keeper therefor, and the two elements will lie locked together.

The arrangement of the parts is such that the bolt will normally lie projected so that the two elements 1 and 2 will become self-locking, for when the element 2 is applied to the head of the post and moved down into its locking position this action will tend to retract the bolt until such time as the bolt is brought into alignment with the slot 4 in the post, whereupon it will again become projected and the two elements then locked together.

After the elements are locked together they may be unlocked by means of a tool *a* having jaws sufficiently small to enter the slit 22 in the element 2, and sufficiently strong to grip onto the head of the bolt around its peripheral edge 18 with sufficient force to withdraw the head and bolt shank upon the withdrawal of the tool, thus unlocking the elements and permitting of their separation.

The head cannot be withdrawn for unlocking the elements by inserting a tool back of the head for lifting it due to the fact that the edge 17 of the head lies so snug to the adjacent wall of the socket, within which the head is contained, as to prevent the entry of a tool for lifting the head.

The lock gives little evidence of the manner of its unlocking. The element 2, simulating as it does a nut, would appear to indicate a part which should be turned by a wrench, but this part will turn freely when the elements are locked together owing to the fact that the slot 4 into which the end of the bolt is fitting is an annular slot which permits free turning of the element 2.

In one type of gas fixture a valve body 25 as shown in Fig. 4, is provided with a flange 26 having an opening in it. The stem 27 of the valve has a flange 28 with one or more openings in it. When the valve is closed the openings in the respective flanges will lie in alignment with one another whereupon the valve body and stem will become locked together, preventing rotation of the stem, by passing the flanged post 1 of applicant's lock through the openings in the respective flanges and then applying the bolt carrying element 2 to the head of the post whereupon the two elements will become locked together, so preventing turning of the valve stem until the lock is opened.

In Fig. 5 is shown another form of closure for a gas fixture. Here a threaded plug 28 is turnable into the end of the pipe for closing it. This plug is provided with a squared head 29 by which the plug may be turned by a wrench. In the application of applicant's lock with such a plug, the plug is provided with a post 1, the nut then taking the place of the flange 3 on the post. With the head of the nut thus fitted with a post

a dome shaped guard 30 is slipped over the post and down over the squared head of the plug preventing application of a wrench thereto. The guard is then locked in place by the application of element 2 of applicant's lock to the head of the post. In such an arrangement both the dome shaped guard and the bolt carrying element 2 are freely rotatable on the post. The squared head of the post is entirely concealed by the guard which cannot be lifted although it may be rotated without affecting the squared head of the plug.

In Fig. 7 another type of fixture is shown in which the end of the pipe is closed, not by a plug as in Fig. 5 but by a cap 32 threaded onto the end of the pipe and formed so as to be turned by a wrench. Here the cap is provided with a post 1 over which is placed a dome shaped guard 33 which envelops the cap for preventing its turning. The guard is held locked in place upon the application of the locking element 2 of applicant's device to the post.

A suitable tool must be employed for retracting the bolt, and as an example of such there is shown in the drawings a tool the body *a*¹ of which bears at its end a set of contracting jaws *a*² annularly arranged. These jaws are contracted by cam surfaces *a*³ thereon against which is moved a tubular slide *a*⁴. The slide is moved by a nut *a*⁵ turning on a threaded portion *a*⁶ on the body *a*¹ of the tool. To prevent the nut being turned off the body of the tool is projected forward beyond the threaded portion thereof, and arranged thereon is a sleeve *a*⁷ held in place by a cross handle *a*⁸ passed through the end of the tool. The sleeve prevents the nut being turned off the end of the tool and the handle enables the body of the tool to be turned within the nut when occasion requires. On turning the nut on the body of the tool the tubular slide will be advanced thereby, and acting upon the cam surfaces *a*³, will contract the jaws *a*² for gripping the head of the bolt for retracting it. The jaws will not be released from the head of the bolt unless the tubular sleeve is drawn back upon a reverse turning of the nut. To this end there is provided a retracting member *a*⁹ which turns with the nut and acts to pull back the tubular sleeve on a reverse turning of the nut, through engagement with a flange *a*¹⁰ on the sliding sleeve *a*⁴, thus releasing the jaws.

I claim:

1. A lock having separable elements lockable together, one element comprising a post having an opening in its side forming a keeper, the other of said elements slidably applied to said post from over the end thereof to embrace said post and cover said opening therein when in lockable position, said other of the elements having a socket opening in the side thereof with a boltway therefrom of lesser size than said socket opening and opening into said opening in said first named element when the elements are combined in lockable position, said bolt assembly comprising a bolt slidable within said boltway, a washer loosely arranged on the shank of said bolt located within said socket forming opening and fixed to the wall thereof, a head fixed to said bolt located within said slotted opening and adapted to have engagement with said washer, and a tension member arranged upon said bolt bearing against said washer and bolt, respectively, for holding said head of the bolt in retractile engagement with said washer.

2. A lock having separable elements lockable

together, one element comprising a post having an opening in its side forming a keeper, the other of said elements slidably applied to said post from over the end thereof to embrace said post and cover said opening therein when in lockable position, said other of the elements having a socket opening in the side thereof with a boltway therefrom of lesser size than said socket opening and opening into said opening in said 5 first named element when the elements are combined in lockable position, said bolt assembly comprising a bolt slidable within said boltway, a washer loosely arranged on the shank of said bolt located within said socket forming opening and fixed to the wall thereof, a head fixed to said bolt located within said socket forming opening and adapted to have engagement with said washer, said head being of less size laterally than said socket forming opening to leave space between the peripheral edge of said head and the adjacent wall of said opening into which a tool may be inserted for retracting said head, and a tension member arranged upon said bolt bearing against said washer and bolt, respectively for 10 holding said head of the bolt in retractile engagement with said washer.

3. A lock having separable elements lockable together, one element comprising a post having an opening in its side forming a keeper, the

other of said elements slidably applied to said post from over the end thereof to embrace said post and cover said opening therein when in lockable position, said other of the elements having a socket opening in the side thereof with a boltway therefrom of lesser size than said socket opening and opening into said opening in said first named element when the elements are combined in lockable position, said bolt assembly comprising a bolt slidable within said boltway, 15 a washer loosely arranged on the shank of said bolt located within said socket forming opening and fixed to the wall thereof, a head fixed to said bolt located within said socket forming opening and adapted to have engagement with said washer, said head having stepped peripheral edge surfaces, one surface adjacent said washer lying snugly adjacent the side wall of said socket forming opening for preventing entrance of a tool for retracting said head, and the other of said surfaces, adjacent the fore end of said head, being spaced from the adjacent side wall of said opening sufficiently to permit of the insertion of a tool for retracting said head, and a tension member arranged upon said bolt bearing against said washer and bolt, respectively, for holding said head of the bolt in retractile engagement with said washer. 20 25

GEORGE H. THACHER.
